UNITED STATES PATENT OFFICE.

WALLACE NOWACKE, OF BROOKLYN, NEW YORK, ASSIGNOR OF ONE-HALF
TO MAX LOESSER, OF SAME PLACE.

HAIR-RETAINER.

SPECIFICATION forming part of Letters Patent No. 673,650, dated May 7, 1901.

Application filed December 18, 1900. Serial No. 40,329. (No model.)

To all whom it may concern:

Be it known that I, WALLACE NOWACKE, a citizen of the United States, residing in New York, borough of Brooklyn, in the State of New York, have invented certain new and useful Improvements in Ladies' Hair-Combs, of which the following is a specification.

This invention relates to an improved hair-comb of that class which is used by ladies for retaining the hair at the back and the side of the head, said comb being inserted into the hair and retained without any especial attaching-pins in any desired position, so as to make up the hair-dress desired; and the invention consists of a lady's hair-comb comprising a row of comb-teeth and a preferably loop-shaped guard to which are attached the said teeth, the main body of the said guard being at one side of and in a plane parallel with the row of teeth, so as to exert a spring action on the hair passed through the teeth in such manner that the teeth are covered by the hair, the spaces between the comb-teeth extending below the lower inner edge of the guard, while the loop-shaped guard is shown up, so as to appear as a buckle.

In the accompanying drawings, Figure 1 is a perspective view showing my improved hair-comb in position at the back of the head. Fig. 2 is a front view of the same removed from the hair and drawn on a larger scale. Fig. 3 is a vertical transverse section thereof, and Fig. 4 is an edge view looking toward the points of the comb-teeth.

Similar letters of reference indicate corresponding parts.

Referring to the drawings, A represents a row of teeth, and B the back of a comb of suitable size, such as used by ladies for retaining the hair in proper position for a head-dress. The comb A B may be made of tortoise-shell, celluloid, metal, or any other suitable material. To the edge of the back B of the comb-teeth A is applied a loop-shaped guard D, which may be made plain or ornamental, so as to simulate a buckle-frame, and which is cemented, riveted, or otherwise fastened to the back of the comb in position parallel therewith and at a short distance from the teeth A, so as to form a space C be-

tween the same and the guard D. The guard can also be made in one piece with the comb, provided a natural tortoise-shell or other one-piece blank is used. When the comb A B is curved, the guard should be parallel with it, 55 as shown in Fig. 2. The spaces between the teeth A extend below the lower inner edge of the guard, so that when the comb is pushed up into the hair at the back or side of the head the hair taken up by the teeth passes 60 over the teeth and below the lower part of the guard D, so as to entirely cover the teeth, but leave the loop-shaped guard entirely exposed as a buckle-like ornament for the hair.

My improved hair-retaining comb is used, 65 preferably, by moving the teeth in upward direction into the hair at the side or back of the head until the hair covers it entirely, in which position it is retained firmly in place by the pressure of the guard on the body of hair between the teeth and guard, so as to require 70 no separate retaining-pins or other similar devices which are now used by ladies in connection with hair-retaining combs heretofore in use.

The advantages of my improved combs are that the comb and guard are made in one structure, either integral or connected, and are thereby at any moment ready for use and application to the head-dress, so as to be conveniently handled when making the toilet and presenting when in position a very neat and ornamental appearance.

Having thus described my invention, I claim as new and desire to secure by Letters 85 Patent—

A lady's hair-comb, consisting of a row of comb-teeth provided with a back, and a loop-shaped guard attached to the back of the comb parallel with the same, the spaces between the comb-teeth extending below the lower inner edge of the guard, substantially as set forth.

In testimony that I claim the foregoing as my invention I have signed my name in presence of two subscribing witnesses.

WALLACE NOWACKE.
